UNITED STATES PATENT OFFICE.

JOSEPH WOLFF, OF BROOKLYN, NEW YORK, ASSIGNOR TO SONORA PHONOGRAPH COMPANY, INC., A CORPORATION OF NEW YORK.

DESIGN FOR A CABINET FOR SOUND-PRODUCING DEVICES.

Application filed August 10, 1925. Serial No. 14,372. Term of patent 7 years.

To all whom it may be concern:

Be it known that I, JOSEPH WOLFF, a citizen of the United States of America, residing in the borough of Brooklyn, county of Kings, city and State of New York, have invented a new, original, and ornamental Design for Cabinets for Sound-Producing Devices, of which the following is a specification, reference being had to the accompanying drawing, forming a part thereof.

This figure is a perspective view of a cabinet for sound producing devices illustrating my new design.

I claim:

The ornamental design for a cabinet for sound producing devices, substantially as shown.

This specification signed and witnessed this 30th day of July, 1925.

JOSEPH WOLFF.
